UNITED STATES PATENT OFFICE.

JAMES K. SMITH, OF CHICAGO, ILLINOIS.

LOOSE-LEAF BINDER.

1,408,480.

Specification of Letters Patent. Patented Mar. 7, 1922.

Application filed February 28, 1921. Serial No. 448,582.

To all whom it may concern:

Be it known that I, SAMUEL K. SMITH, a citizen of the United States, residing at Chicago, in the county of Cook and State of

Illinois, have invented certain new and useful Improvements in Loose-Leaf Binders, of which the following is a specification.

This invention relates to loose-leaf binders.

10. It relates more particularly to loose-leaf binders wherein the insertable leaves are held by cords.

One of the objects of the invention is to provide an improved loose leaf binder.

15. Another object is to provide an inexpensive and readily operable clasp for adjustably anchoring the binder cord.

Another object is to provide a clasp which allows ready insertion and adjustment of 20 the cord.

Other objects and advantages will hereinafter appear.

An embodiment of the invention is illustrated in the accompanying drawing, where- 25 in:

Fig. 1 is a perspective of an open loose-leaf binder.

Fig. 2 is a perspective of the clasp in cord gripping position.

30. Fig. 3 is a longitudinal section of the clasp in cord gripping position.

Fig. 4 is a longitudinal section of the clasp in non-gripping position, and

35. Fig. 5 is a cross section of the anchor on the line 5—5 of Fig. 3.

The binder comprises, in general, a pair of side covers 1, and a back 2. The side and back covers may be made of any appropriate material and are hinged together 40 in any suitable and approved manner.

At the junction of each side cover and the back there is hinged a small stiff flap 3. Between these flaps the separable leaves of the book are detachably secured. The flaps 45 may be made of the same material as the covers and may be reenforced and stiffened by metal strips 3' if desired.

For double perforated leaves, each flap is provided with two holes 4 and 5, which 50 align with the corresponding holes in the other flap. Over each hole in one flap there is secured the base plate 6 of one of the clasps.

Base plate 6 may be formed from sheet 55 metal and is provided with a hole 7 aligning with the corresponding hole in the flap.

The base plate may be secured to the flap by suitable means such as rivets 8. The opposite edges of the base plate are inturned to provide a channeled guideway for a slide 60 or catch 9 of the clasp. Slide 9 may also be made of sheet metal. One end of the slide is bent at right angles to the body of the slide to form a finger hold 10. The other end of the slide is bent to provide a slightly 65 projecting latch 11. The slide has a hole 12 therethrough.

The slide fits loosely within the guideway of base plate 6 so that it may be moved readily therethrough.

70. To thread the binder the ends of a suitable cord 13 are passed through the holes in the flap on which there are no catches. The ends of the cord are passed through the holes in the leaves to be bound. Then the 75 slides are moved along the guideways in the base plate until the openings therein align with the corresponding openings in the flap and base plate, as shown in Fig. 4, and the ends of the cord are passed therethrough. When the cord has been drawn sufficiently taut the slides are pushed forward until their latches 11 come beyond the ends of the respective base plates. The resiliency of the cord and clasp members, 80 which give enough to allow the slide to be thus moved, cause the slide to spring outwardly locking the latch behind the edge of the channels of the base plate. The parts are then in the position shown in Fig. 3 and 90 the ends of the cord are anchored.

To release the cord it is only necessary to slightly depress the end of the slide by pushing inwardly on latch 11 and by means of hand hold 10 move the slide back until 95 its opening aligns with the holes in the base plate and flap.

Having described my invention what I claim as new and desire to secure by Letters Patent, is:

100. 1. A loose-leaf binder having side and back covers, a pair of flaps secured to the cover and having openings therethrough, a channeled base plate secured to one flap and having an opening aligning with the opening in the flap, a slide fitting in the channeled base plate and having an opening which in one position of the slide aligns with the opening in the base plate and in another position of the slide is displaced 105 relative to the opening in the base plate to carry and clamp a cord between the slide 110

and base plate, and means for positively holding the slide in cord clamping position.

2. A loose-leaf binder having side and back covers, a flap secured to the cover and having an opening therein, a base plate secured to the flap and having an opening therein aligning with the opening in the flap, a catch slidably carried upon the base plate and having an opening aligning with the opening in the base plate in one position and displaced therefrom in another position to carry and clamp a cord between the base plate and catch, and means for positively retaining the catch in cord clamping position.

15 3. A clasp for a loose-leaf binder cord comprising a channeled base plate for attachment to a binder and having an opening therethrough, and a slide movably secured to the base plate and having an opening there-
10 in which aligns with the opening in the base plate in one position of the slide and is displaced therefrom in another position of the slide, and means for latching the slide in the second mentioned position.

15 4. A clasp for a loose-leaf binder comprising a base plate having its opposite edges bent to form a guideway and having an opening therethrough, a slide movably held in the guideway and having an opening

therethrough which in one position of the slide aligns with the opening in the base plate and in another position of the slide is displaced from the opening in the base plate, and a projection on the slide cooperating with the base plate positively to hold the slide in the second mentioned position.

5. A loose-leaf binder having side and back covers; a flap hinged to one of the covers and having an opening therethrough; and a cord anchoring clasp secured to the flap and comprising a base plate having an opening aligning with the opening in the flap, a plate slidably mounted on the base plate and having an opening therethrough, the opening in the slide aligning with the openings 45 in the base plate and flap in one position of the slide so that a cord may be passed through all the openings and being out of alignment with the openings in the base plate and flap in another position of the slide so 50 that a cord is clamped between slide and base plate, and a latch on the slide for cooperat-
ing with the base plate to hold the slide in cord clamping position.

In testimony whereof I hereunto sub- 55 scribed my name.

SAMUEL K. SMITH.
